US0D1015204S

(12) **United States Design Patent** (10) **Patent No.:** **US D1,015,204 S**
(45) **Date of Patent:** **** Feb. 20, 2024**

(54) **ZIPPER CHARM**

(71) Applicant: **ZIPJEWEL, Inc.**, San Rafael, CA (US)

(72) Inventor: **Phil Martino**, San Rafael, CA (US)

(73) Assignee: **ZIPJEWEL Inc.**, San Rafael, CA (US)

(**) Term: **15 Years**

(21) Appl. No.: **29/738,003**

(22) Filed: **Jun. 13, 2020**

Related U.S. Application Data

(63) Continuation of application No. 16/025,998, filed on Jul. 2, 2018, now Pat. No. 10,736,385.

(57) **CLAIM**

The ornamental design for a zipper charm, as shown and as described.

DESCRIPTION

FIG. 1 is a top perspective view of a zipper charm in accordance showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines included in FIGS. 1-2 are for the purpose of illustrating environmental structure of a sample design on the zipper charm and form no part of the claimed design.

1 Claim, 7 Drawing Sheets
